F. G. Fischer,

Attorney.

UNITED STATES PATENT OFFICE

110,033

DESIGN FOR A TAX TOKEN DISPENSING MACHINE

Ora F. Murphy, Minneola, Kans.

Application November 1, 1937, Serial No. 72,542

Term of patent 7 years

To all whom it may concern:

Be it known that I, Ora F. Murphy, a citizen of the United States, residing at Minneola, in the county of Clark and State of Kansas, have invented a new, original, and ornamental Design for Tax Token Dispensing Machines, of which the following is a specification, reference being had to the accompanying drawing, forming a part thereof, in which:

Fig. 2 is a plan view thereof.

I claim:

The ornamental design for a tax token dispensing machine, as shown.

ORA F. MURPHY.
